UNITED STATES PATENT OFFICE.

SIGMUND L. GOLDMAN, OF CHICAGO, ILLINOIS, ASSIGNOR TO RED SUN PRODUCTS CO., OF CHICAGO, ILLINOIS, A CORPORATION OF ILLINOIS.

BOTTLE-CAPPING MACHINE.

Application filed August 1, 1927. Serial No. 209,708.

My invention relates, more particularly, to bottle-capping machines comprising an upright having a base and carrying a capping-head and means on the head engaging the upright and by which the desired cap- applying pressure is exerted against a cap applied to a bottle positioned on the base.

My objects, generally stated, are to provide improvements in the means for securing the upright to the base to the end that the upright will be rigidly secured in position and resist the stresses to which it is subjected in the capping operation, by a novel, simple and inexpensive construction; to provide a novel, simple and inexpensive arrangement of parts operative to effect the automatic lifting of the capping-head to normal position after release by the operator of the means for forcing the capping-head to cap-securing position; and other objects as will be manifest from the following description.

Referring to the accompanying drawing:—

Figure 1 is a side view of the machine. Figure 2 is an edge view thereof. Figure 25 3 in a detail view of the capping-head of the machine, this view being taken at line 3—3 on Fig. 5 and viewed in the direction of the arrows. Figure 4 is a view in edge elevation taken at the line 4 on Fig. 3 and viewed in the direction of the arrow. Figure 5 is a section taken at the line 5 on Fig. 3 and viewed in the direction of the arrow. Figure 6 is a section taken at the line 6 on Fig. 3 and viewed in the direction of the arrow. Figure 7 is a plan section taken at the line 7 on Fig. 1 and viewed in the direction of the arrow. Figure 8 is a broken sectional view taken at the line 8 on Fig. 1 and viewed in the direction of the arrow; and 40 Figure 9, a sectional view taken at the line 9 on Fig. 7 and viewed in the direction of the arrow.

The construction of capping mechanism illustrated comprises generally a base 10, an upright 11 secured to and rising from the base 10 adjacent an edge thereof, a capping- head 12 slidable up and down on the upright 11 and means for actuating the head 12.

The base 10, preferably formed from sheet metal, is formed with upwardly-deflected portions 13 creating laterally-directed openings 14 shown as parallel and opening in opposite directions at the upper face of the base.

55 The upright 11 is formed of two bars 15

having straight upper portions 16 at which they fit flatwise together and are riveted in position as represented at 17. The lower ends of the bars 15 are deflected downwardly and outwardly relative to each other and therefore convergent, their lower extremities being bent inwardly in opposite directions to present substantially horizontal lugs 18.

The lug-portions 18 of the upright extend through the openings 14 and underlie the raised plate portions 19 of the deflected portions 13 in which positions they are rigidly secured to the base 10 by rivets 20 extending through the lugs 18 and the plate portions 19.

The bars 15 are preferably secured together as stated before assembly with the base and to assemble them with the base are sprung outwardly at their inclined lower portions to enter the lugs 18 in the openings 14.

The body of the capping-head 12 is preferably formed of a single sheet of metal bent into general U-shape to present the substantially parallel spaced-apart side plate-portions 21 at which the head straddles the upper portion of the upright 11, these plate-portions 21 being riveted together at 21^a. The cap-engaging die-portion of the head 12, which may be of any desirable form such, for example, as commonly provided in machines for this purpose, is represented at 22 and is rigidly connected to the plate-portions 21 at outwardly bent lugs 21^b on the bottom edge-portions of these plate-portions.

The means for actuating the capping-head 12 comprise a rack 23 on the upper bar-portion of the upright 11, this rack in the particular construction shown, being formed by cutting teeth in the adjacent edges of the straight portions of the bars forming the upright. The rack is provided for cooperation with the segmental gear-portion 24 of a lever 25 which is located between the plate-portions 21 and is fulcrumed on a pin 26 carried by these plate-portions and so positioned as to cause the lever to mesh at its gear-portion with the rack 23. The lever is so formed as shown that when it is swung to uppermost position, generally parallel with the upright, the gear-portion 24 is disengaged from the rack 23 and the capping head with the parts carried thereby may be freely adjusted along the rack to any desired position of initial engagement of the gear with the rack for bottles of different heights, or, if desired, may be lifted free of the upright to 110

disengage the head from the upright, this being especially desirable where it is desired to reverse the position of the head on the upright, in which position the lever depends, as for example to economize in the space occupied by the machine which is an important factor especially in shipping.

The arrangement of the parts is such that in the initial engagement of the gear with the rack the lever 25 extends in an upward direction and the capping pressure applied to a cap on a bottle positioned on the base 10, is exerted by swinging the lever outwardly and downwardly, the head in this operation descending.

To provide for the normal positioning of the head and lever in raised position, with the die-portion 22 clear of the bottle and the return of these parts to such position after the capping operation, I provide a coil spring 27 which is located between the plate-portions 21 at the open edge of the head, one end of this spring being releasably connected with the head by a split pin 28 extending through the plate-portions 21 and through an eye 29 on the spring and its other end being connected by an eye 30 thereon, with the lever as shown, these parts being so arranged that in the rocking of the lever 25 to depress the capping head the spring is placed under sufficient tension to throw the lever 25 upward and raise the head and lever when the operator discontinues downward pressure thereon.

The spring 27 is somewhat wider than the lever and to permit of the free operation of the spring, I preferably outwardly deflect those portions of the plate-portions 21 adjacent to which the spring extends, as represented at 31, and as a convenient and simple means of forming a stop for the lever 25 in its downward swinging movement, I indent the edges of the plate-portions 21 as represented at 32.

It will be understood from the foregoing that a machine embodying my improvements is not only of simple and inexpensive construction but is rugged and highly resistant to the stresses imposed on it in use. Furthermore, the machine comprises the minimum number of parts and adapts itself to replacements, in case of impairment of parts, with quick facility, this being especially the case as regards the spring which, as will be noted, by being located as shown and described, does not require for its attachment the use of a separate plate or bracket on the head and by being secured in place in accordance with the

showing may be readily removed and substitution of another therefor quickly and easily effected.

The manner of securing the upright to the base is of importance as the necessary resistance to separation of the upright from the base in the capping operation is presented by simple and inexpensive means, the main stresses being taken by the deflected portions of the base and the lugs on the upright.

While I have illustrated and described a particular embodiment of my invention, I do not wish to be understood as intending to limit it thereto as the same may be variously modified and altered without departing from the spirit of my invention.

What I claim as new and desire to secure by Letters Patent is:

1. A capping machine comprising a base on which the article to be capped is supported, an upright rising therefrom and provided with a capping element, said base being formed with upwardly-deflected portions having lateral openings at the upper surface of said base and said upright being formed of legs having laterally-extending portions extending through said openings and beneath said deflected portions, and means securing said upright in position on said base. 75

2. A capping machine comprising a base on which the article to be capped is supported, an upright rising therefrom and provided with a capping element, said base being formed with upwardly-deflected portions having lateral openings at the upper surface of said base and said upright being formed of resilient legs connected together and spaced apart at their lower ends, the lower ends of said legs having laterally-extending portions extending through said openings and beneath said deflected portions and means securing said legs in position on said base. 90

3. A capping machine comprising a base on which the article to be capped is supported, an upright rising therefrom and provided with a capping element, said base being formed with upwardly-deflected portions having lateral openings at the upper surface of said base and extending in opposite directions and said upright being formed of legs having oppositely-extending laterally-disposed portions extending through said openings and beneath said deflected portions, and means securing said upright in position on said base. 100
